UNITED STATES PATENT OFFICE.

HORACE SEE, OF NEW YORK, N. Y.

DESIGN FOR A BEARING.

SPECIFICATION forming part of Design No. 31,829, dated November 14, 1899.

Application filed June 10, 1899. Serial No. 720,096. Term of patent 14 years.

To all whom it may concern:

Be it known that I, HORACE SEE, of the city, county, and State of New York, have invented and produced a new and original Design for 5 Bearings, of which the following is a specification.

The essential feature of my design is a projection on one face of the body of the bearing and a semicylindrical recess appearing in said 10 body and projection.

The drawing represents my design in perspective.

The upper face A of the body B of the bearing is flat. On one face C of said body is a projection D. A semicylindrical recess E appears transversely the face A and also in the projection D. 15

I claim—

The design for a bearing substantially as herein shown and described.

HORACE SEE.
